MILK BOTTLE RECEIVER

Application filed May 4, 1931. Serial No. 534,858.

This invention relates to means for holding milk bottles and the like and has for one of its primary objects the provision of means for preventing the theft of milk bottles, 5 filled or empty.

Milk is now commonly delivered in bottles from house to house on a regular route, the delivery man picking up empty bottles and leaving filled bottles as he goes along the 10 route. In many cases, he delivers the milk in the early morning hours before the consumer arises and the empty bottles are, therefore, generally set out the night before and the filled bottles are left on a porch or 15 step subject to be stolen or knocked over.

Our invention is designed to prevent empty bottles from being knocked over and broken and to prevent the filled bottles from being removed after delivery by unwar- 20 ranted persons. Also, our invention provides a neat receptacle for holding bottles up off the floor and provides for the easy reception or removal of the bottles. It further provides a safe place for retaining 25 a check or card to be picked up by the delivery man.

A further object is to prevent removal of the bottle caps and to cover the caps to prevent dirt from accumulating thereon.

30 These and other objects will become apparent in the following description of the invention as shown in one particular form in the accompanying drawing, in which

Fig. 1 is a fragmentary front elevation of 35 a structure embodying our invention;

Fig. 2, a fragmentary top plan view of one end of the structure;

Fig. 3, a fragmentary side elevation of the structure with the cover open; and

40 Fig. 4, a similar fragmentary side elevation with the cover closed.

Like characters of reference indicate like parts throughout the several views in the drawing.

45 We form a back plate 10 here shown as being provided with a plurality of holes 11 therethrough to receive screws or the like therethrough to attach the plate to the side or wall of a house (not shown). A shelf 12 projects forwardly from the bottom edge of

the plate 10 and has the ends 13 and 14 joining therebetween to serve as braces. Preferably, the shelf slopes upwardly somewhat away from the plate. The shelf is cut out from its forward edge to have U-shaped 55 notches 15 therein, here shown as two in number, of just sufficient size and of proper shape to receive therein the necks of milk bottles 16 whereby the overhanging ring 17 about the mouth of the bottles may rest on the shelf to permit the bottles to hang thereby. The edges of the notches 15 are turned 60 downwardly to form the flange 18 therearound to reinforce the shelf and prevent the bending of it.

A box-like cover 19 is pivoted by its ends to the ends 13 and 14 so as to be free to be rocked therebetween and has a lock 20 on its forward side which has a projecting 70 spring latch 21 adapted to engage an edge of the slot 22 formed in the forward edge of the shelf 12, when the cover is dropped down. The cover 19 is so pivoted that when it is in the open position it is tilted back from the vertical position somewhat so as 75 to lean rearwardly against the plate 10. In that position, the rear side 23 of the cover extends forwardly a distance over the rear part of the notch 15.

Now when a bottle 16 is entered into a 80 notch 15, the bottle ring 17 strikes the cover side 23 and pushes it rearwardly to rock the cover around from the position in Fig. 3 to cause it to drop forwardly to the position in Fig. 4 to cause the cover then to be locked 85 to the shelf 12 by the latch 21 springing into place. The forward wall 24 of the cover then extends downwardly sufficiently to prevent the withdrawal of the bottle from the notch, and the bottle is thus securely held 90 until the lock 20 is operated to release the latch 21 to permit raising of the cover.

The cover 19 is provided with spring clips 25 as means for retaining therein milk tickets, checks, money, or the like for the attention of the delivery man, and suitable advertising matter or identification may be displayed on the plate 10 above the cover. Both the consumer and the delivery man 95 may be supplied with keys to the lock. The 100

consumer places the empty bottles in the receiver and closes the cover 19. When the delivery man arrives he unlocks the lock 20, raises the cover 19 and swings it back against 5 the plate 10, slips out the empty bottles and slips in the filled bottles to cause them to rock the cover which drops automatically to the locked position, and the delivery man goes on his way.

10 While we have here shown and described our invention in the best form as now known to us, it is obvious that structural changes may be made without departing from the spirit of the invention, and we, therefore, 15 do not desire to be limited to that precise form, nor any more than may be required by the following claims.

We claim:

1. In a receiver for bottles having a laterally projecting ring around their mouths, holding means for suspending a bottle by said ring, and a bottle cover mounted to swing past a vertical plane in opening, said cover having a rear lateral flange which is 20 contacted by the bottle to automatically close the cover over the bottle mouth by contact of the bottle with the cover flange. 80
2. In a receiver for bottles having a laterally projecting ring around their mouths, holding means for suspending a bottle by said ring, and a bottle cover mounted to swing past a vertical plane in opening, said cover having a rear lateral flange which is 25 contacted by the bottle to automatically 90 close the cover over the bottle mouth by contact of the bottle with the cover flange, and lock means carried by the cover to prevent removal of the bottle from the holding means. 95
3. In a receiver for bottles having a projecting ring about their mouths, a shelf having a back plate and a notch formed in the shelf opening from an edge thereof adapted to receive the neck of a bottle 30 within the notch to permit the bottle to be 100 suspended from said ring, and a box-like cover comprising a rectangular plate having lateral front, back and end walls with sides pivoted to swing off-center when raised into 45 stopping contact with the back plate, and with its back side extending over said notch in the path of a bottle inserted in the notch to cause said cover to drop over said notch by pressure of the bottle against said side. 110
4. In a receiver for bottles having a projecting ring about their mouths, a shelf having a back plate and a notch formed in the shelf opening from an edge thereof adapted to receive the neck of a bottle within the 50 notch to permit the bottle to be suspended 115 from said ring, and a box-like cover comprising a rectangular plate having lateral front, back and end walls with sides pivoted to swing off-center when raised into 60 stopping contact with the back plate, and 120
5. In a receiver for bottles having a projecting ring about their mouths, a shelf having a back plate and a notch formed in the shelf opening from an edge thereof adapted to receive the neck of a bottle within the 65 notch to permit the bottle to be suspended 125 from said ring, and a box-like cover comprising a rectangular plate having lateral front, back and end walls with sides pivoted to swing off-center when raised into 70 stopping contact with the back plate, and 130

with its back side extending over said notch in the path of a bottle inserted in the notch to cause said cover to drop over said notch by pressure of the bottle against said side, and a lock automatically securing the cover to the shelf upon the cover being dropped thereon. 70

In testimony whereof we affix our signatures.

CORNELIUS B. OSTER.
HARRY RAINES.
